DESIGN FOR A STREET-SWEEPER BODY

Manuel Adrian, San Jose, Calif.

Application July 22, 1943, Serial No. 110,734

Term of patent 14 years

To all whom it may concern:

Be it known that I, Manuel Adrian, a citizen of the United States and residing in San Jose, in the county of Santa Clara and State of California, have invented a new, original, and ornamental Design for Street-Sweeper Bodies, of which the following is a specification, reference being made to the accompanying drawing, forming a part thereof.

In the drawing:

Figure 1 is a perspective view of the street-sweeper body embodying my new design, viewed from one side.

Figure 2 is a perspective view of the street-sweeper body, viewed from the other side.

Figure 3 is a rear elevational view of the same.

I claim:

The ornamental design for a street-sweeper body, as shown.

MANUEL ADRIAN.
